UNITED STATES PATENT OFFICE.

ALBERT F. PRESTON, OF BOSTON, MASSACHUSETTS, ASSIGNOR TO THE
BUSELL LASTING MACHINE COMPANY, OF SAME PLACE.

LASTING-MACHINE.

SPECIFICATION forming part of Letters Patent No. 597,247, dated January 11, 1898.

Application filed April 30, 1897. Serial No. 634,612. (No model.)

To all whom it may concern:

Be it known that I, ALBERT F. PRESTON, of Boston, in the county of Suffolk and State of Massachusetts, have invented certain new and useful Improvements in Lasting-Machines, of which the following is a specification.

This invention has relation to lasting-machines of the type shown in my copending application, Serial No. 599,223, filed July 15, 1896; and it consists in the novel features of construction and relative arrangement of parts clearly illustrated upon the accompanying drawings, fully described in the following specification, and particularly pointed out in the appended claims.

Reference is to be had to the accompanying drawings, and to the letters and figures marked thereon, forming a part of this specification, the same letters and figures designating the same parts and features, as the case may be, wherever they occur.

Of the drawings, Figure 1 represents in side elevation a machine embodying my invention. Fig. 2 represents in plan view the head carrying the wipers for the heel end of the last. Fig. 3 represents a side elevation of the same. Fig. 4 represents a rear end elevation thereof. Fig. 5 represents the same in plan view with the top plate removed, so as to expose the wipers. Fig. 6 represents a cross-section on the line 6 6 of Fig. 2. Figs. 7, 8, 9, and 10 are views similar to Figs. 2, 3, 4, and 5 and showing the head and the wipers for the toe end of the last. Figs. 10^a, 10^b, and 10^c are detail views illustrating the disk coupler for the wipers. Fig. 11 represents a longitudinal section through the head, taken on the line 11 of Fig. 7. Fig. 12 represents the heads in plan view, partially in section, with the top plates and wipers removed, so as to show the band and its carriers for clamping the upper to the last. Fig. 13 represents the band and carriers at the toe end when in their operative positions. Fig. 14 is a perspective view of the band and carriers detached. Fig. 15 represents the band as being formed in two independent parts. Figs. 16 to 19, inclusive, show other forms of wipers.

Referring to the drawings, which show the form of my invention which I have selected

for the sake of illustration and to which I do not wish to be understood as limiting myself, *a* indicates a standard upon which is revolvably mounted a bed *a'*, having formed thereon or secured thereto a stationary carrier *a''*. A movable carrier *a'''* is arranged to slide in a guideway in the bed, movement being imparted thereto by any suitable means, such as a hand-wheel *b*, rotating pinions *b'*, which engage rack-bars *b''*, connected to the stationary carrier. Upon the carrier are pivoted heads *c c'*, which may be adjusted to any desired angle and upon which are placed wipers for automatically wiping the edges of the upper over the sole of the last at the toe and heel, and bands for clamping the upper to the last during the wiping operation.

Mounted upon the bed is a standard *a⁴*, which may be adjusted vertically by any desirable adjusting means and which is formed or provided with a spherical or ball-like end *a⁵*. A cap *a⁶*, having a socket to receive the spherical end *a⁵*, is placed upon the standard and has a convex upper surface to receive the top of the last when the latter is in the machine. This standard relatively to which the last is forced horizontally coacts with the curved top thereof in such way as to jack the last vertically against the wipers both at the toe and at the heel.

Referring to Figs. 2 to 6, inclusive, and to Fig. 12, the head *c* has pivoted thereto by a pivot *d* a tilting bolt *d'*, having a flange *d²* and a threaded portion *d³*. Pivoted to the outer end of the head by a screw *d⁴* in axial alinement with the pivot *d* for the bolt *d'* is a cross-bar *d⁵*, the upper edge of the said cross-bar *d⁵* being in alinement with the upper edge of the flange *d²*. Resting upon the flange *d²* of the bolt *d'* is a top plate *e*, which is provided at its rear edge with a depending flange *e'*, resting upon the cross-bar *d⁵*, said flange *e'* being formed upon the top plate *e* or else secured thereto by screws *e²*, as shown. The top plate is provided with an aperture adequate to receive the bolt *d'*, to which it is rigidly secured by a nut *d⁶* and a washer *d⁷*. By reason of the pivot *d* and the pivot-screw *d⁴* being in alinement and being arranged in the central longitudinal line of the head the plate *e* may be tilted, as shown in Fig. 6, relatively to the stationary head *c*.

Projecting downwardly from the sides of the top plate *e* are guide-bars *e*² *e*², having inwardly-projecting flanges *e*³, and inserted between said flanges and the under face of the top plate *e* are wipers *ff* and the carriers *g* *g* for the band *h*. The said band-carriers are similar in shape, as shown in Fig. 14, and have their outer edges *g*' resting against the guide-bars *e*². Their inner edges are cut away to form a curve, so as to receive between them the heel of a last, and they are provided at their edges with upwardly-projecting strengthening curved flanges *g*², to which the band is secured. This band may be formed of any suitable flexible material, although I prefer leather, and operates to bind the upper firmly to the end of the last. It projects downward below the flanges *g*², as shown in Fig. 3, and it serves to unite the two carriers *g* *g* flexibly together at the point 2, as shown in Figs. 12 and 14. It will be observed that the edges *g*' *g*' are curved, as at 3 3, the curves being arcs of a circle struck from the point 2, the diameter of the circle being equal to the distance between the guide-bars *e*². The flanges *g*³, which are continuations of the flanges *g*², abut against movable pins *g*⁴, passed horizontally through the head *c*. Between the flanges *g*³ on the pins and a bar *g*⁶, which is secured in a slot in the head, are placed springs *g*⁷, encircling the pins *g*⁴, so that the ends of the pins are held yieldingly in contact with the band-carriers, each bearing against only one of the carriers *g*, so that the latter may be moved relatively to each other, as desired.

Inserted between the top surfaces of the carriers *g* and the under surface of the plate *e* are the two loosely-mounted wipers *ff*. They are similar to each other in plan view, each having its inner edge *f*' curved to correspond to the heel of a last. They are cut away, as at *f*², so as to escape the bolt *d*' and its flange *d*², and they rest at their rear ends upon the cross-bar *d*³. They are closely confined between the guide-bars *e*² *e*² and are each provided with a recess having a curved edge 5, which is an arc of a circle struck from the point 4 and whose diameter is equal to the distance between the guide-bars *e*², said point 4 being the meeting-point of the front inner corners of the wipers. The rear inner edges are inclined and diverging and are formed with rack-teeth *f*³, with which two intermeshing pinions *f*⁴ *f*⁴ engage, said pinions being mounted to turn loosely upon studs *f*⁵, projecting upwardly from the head *c*. The wipers are provided with rearwardly-projecting pins *f*⁶, connected by a strong tension-spring *f*⁷, and they are also provided with downwardly-projecting studs *f*⁸, against which the rear edges of the carrier *g* *g* for the band may engage, as shown in Figs. 5 and 12, to limit the movement of the wipers over the heel. Now it will be seen that the upward and rearward pressure of a last against the wipers will cause a rearward movement of the

wipers, whereupon the inclined edges will be separated by the pinions and the curved edges *f*' *f*' of the wipers will be swung toward each other about the point 4, which point moves in a straight line toward the pivot *d*', the guide-bars *e*² coacting with the curved edges 5 of the wipers in holding the corners of the wipers together at the said point 4, so that the said corners are always in contact. The wipers being engaged in the rear of the point 4 by the pinions *f*⁴ *f*⁴, they must necessarily move in unison, for the swinging movement of one wiper will cause a simultaneous corresponding movement of the other.

The carriers for the band *h*, although entirely disconnected from the wipers, swing toward each other about the point 3, so that the band firmly clamps the upper against the heel at all points along its length.

The curved edges 3 3 of the carriers cooperate with the guide-bars *e*² in holding the corners of the carriers together at the point 3 as the point moves in a straight line toward the pivot-bolt *d*'. Besides operating as a clamp for the upper, the band and its carriers act as stops in limiting the movement of the wipers inward over the sole of the last, since the flanges *g*³ of the carriers engage the stops or pins *f*⁸ of the wipers, the said pins being normally a short distance from the curved edges *f*' of the wipers. The springs *f*⁷ and *g*⁷ immediately return the wipers and the band-carriers to their normal positions as soon as the pressure of the last upon the band and the wipers ceases.

Springs *i* *i* are secured to the head *c* and bear upwardly against the band-carriers *g* *g* to assist the flanges *e*³ of the guide-bars *e*² in holding the said carriers and the wipers against the top plate *e*. By reason of the said top plate being pivoted to swing upon a substantially horizontal axis the wipers and the band are adapted to accommodate themselves to a last having the plane of the sole at the toe at an angle to the plane of the sole at the heel, so that when the last is pressed against the band and the wipers not only do the latter automatically adjust themselves, but they automatically operate independently of any power devices.

Now, referring to Figs. 7 to 11, inclusive, and to Fig. 13, I have shown the pivot-bolt *j*, which corresponds to the bolt *d*', as being rigidly secured in the head *c*' instead of tilting, it being provided with a flange *j*', additional to the flange *j*², for this purpose. The top plate *h* is pivoted on the bolt *j* by a nut *j*³ and washer *j*⁴, so that the plate is capable of swinging horizontally or in planes parallel to the upper surface of the head *c*'. The wipers *ll* have front inner curved edges *l*' to fit over the toe of the last and are provided with the inwardly-projecting lugs *l*² to rest upon the last when the latter is first placed in the machine. They are cut away, as at *l*³, to escape the bolt *j*, and they are provided on their inner edges with a semicircular recess and a semicircular

flange to extend into a groove m' in a disk coupler m , which is placed between them so as to couple them together and cause their movements to be simultaneous, besides providing a continuation of the curved edges l l' of the wipers. The curved edges 7 7 of the recess 4 in the sides of the wipers are arcs of a circle struck from the point 8, which is the center of the coupler m , the diameter of the circle being equal to the distance between the guide-bars $k' k'$, extending downward from the top plate k . That portion of the flange m' of the coupler m which is exposed between the corners 9 9 of the wipers forms a continuation of the curved edges l of the wipers unless the wipers are in such position that the corners abut.

Instead of providing pinions f^5 f^5 to operate the wiper I may employ rollers n n , loosely mounted on studs n' n' , projecting upward from the head c' , and the wipers are provided with the inclined edges 10 10, which coact with the rollers in forcing the outer end of the wipers outward and the front ends thereof inward when the said wipers are moved longitudinally to the rear. Thus by providing the coupler which engages the two wipers I am enabled to dispense with the pinions and the gear-teeth and to employ the rollers and the straight inclined edges for separating the rear ends of the wipers.

The spring o , having its ends connected to pins $o' o'$, projecting rearward from the wipers, is provided for returning the wipers to their inoperative positions when pressure upon the same ceases.

Below the wipers are placed the carriers p p for the band q , which are constructed substantially as hereinbefore described, and they bear against the independently movable yielding pins $p' p'$, passing through apertures in the head c' . The head is stationary against rotation, while the cap and the wipers are free to rotate about the pivot j , so that the said wipers will automatically adapt themselves to a last having the median line of the toe inclined to the median line of the heel, as shown in Fig. 13, and as the pins p' are independent the carriers and the band also automatically adjust themselves to the last, as they are free to slide between the wipers and the springs r r , which hold them against the under faces of the wipers. The band and the carriers are entirely independent of the wipers in this case, nor are there projecting stop-pins carried by the wipers to be engaged by the said carriers to limit the movements of the wipers. When upward and rearward longitudinal pressure is exerted against the band and the wipers, the wipers are forced rearwardly and the curved edges move toward each other over the sole of the last, said wipers swinging about the point 8 and being held inward by the engagement of the curved edge 7 with the guide-bars k' .

In using the machine for lasting the last is inverted and is placed between the carriers,

with its top resting upon the standard. Then by means of the hand-wheel the movable carrier is forced toward the stationary carrier, 70 with the result that the last is jacked vertically against the wipers both at the toe and the heel. The longitudinal pressure against the said wipers and the bands causes the bands to firmly embrace the ends of the last 75 to clamp the upper thereagainst, and it causes the wipers to swing automatically over the edges of the upper and the sole of the last to draw the said edges taut. As I have before stated, the wipers and the band are independent of each other and are not connected together, and although the wipers swing about a given moving point they too are disconnected and are pivoted neither to each other nor to the head of the carrier. 80

Although I prefer to employ the movable band and its carriers, yet they are not absolutely necessary to the lasting operation, as the wipers are automatically operated without them by the engagement therewith of the last and upper. 90

By mounting the wipers on one of the carriers to tilt vertically or perpendicularly to the head and the wipers on the other head so as to swing in planes parallel to the head 95 they automatically adapt themselves to a last of any shape or size, whether the plane of the sole at the heel be at an angle to the plane of the sole at the toe or whether the median line of the last at the toe be at an angle to 100 the median line thereof at the heel. Thus the upper is drawn taut both at the toe and the heel merely by causing the two sets of wipers to approach each other, since the last sliding on the standard is jacked vertically to provide the necessary upward pressure upon the wipers. 105

In Fig. 13 I have shown by full and by dotted lines how the band and its carriers automatically adapt themselves to differently-shaped lasts, although the head upon which they are mounted is relatively stationary. This is accomplished by placing the carriers in guides on the head to slide freely and loosely and by placing the spring-pressed pins 110 or fulcrums on both sides of the central line of pressure, so that the two carriers will, by the wedging pressure of the toe between said pins or fulcrums, be swung toward each other 115 to clamp the band against the upper and last. 120

The band may be formed in two independent halves s s , each half being secured to one of the carriers, as shown in Fig. 15, and by reason of the curved edges 7 7 engaging the guide-bars k' the ends 2 of the said halves s s 125 do not separate, but remain in contact, so as not to injure or mar the shoe. Hence, though the wipers and the band are independently movable and are independently mounted upon a support, they are automatically operated by the engagement of a last therewith, 130 and both automatically adapt themselves to different shapes and sizes of lasts.

Both the toe and the heel wipers are cou-

pled together to cause their movements to be simultaneous or in unison. The coupler for the toe-wipers performs two functions, for in addition to compelling them to move in unison and to the same extent it forms a continuation of the operative edges thereof, being also flush with their under or operative surfaces, so as to prevent the upper from being dented or marred in any way, and the coupler for the heel-wipers—*i. e.*, the rack-teeth on the diverging edges of the wipers and the teeth of the pinions—not only causes a simultaneous movement of the wipers, but it acts as a wedge to separate their rear ends and force their operative edges toward each other.

From the foregoing it will be observed that many changes may be made in the machine and the mode of operation thereof without departing from the spirit and scope of my invention. It is evident that the supports for the wipers and the band-carriers may be constructed to meet any particular requirements as to shape and lightness and may be changed from their present locations.

In Figs. 16 to 19, inclusive, I have illustrated the toe-wipers as being arranged to operate without a coupler in the form of a disk, in which case the meeting inner corners of the wipers always remain in contact, being similar in this respect to the heel-wipers before described. The two wipers *t* are placed between the cap-plate *u* and the head *v* and are connected at their rear ends by the spring *w*. For the purpose of providing wedges for separating the rear ends of the wipers the wipers are formed with diverging slots *t' t'*, into which project pins *u' u'*, depending from the cap-plate *u*, and for holding the corners in contact at the point 15 the plates are formed with slots *t' t'* to receive pins *u' u'*, projecting down from the said cap-plate. Thus it will be seen that the wipers when operated by the engagement of a last therewith will have their operative edges automatically swung toward each other. A coupler consisting of a curved bar *x* is placed in a groove in the wipers to cause the wipers to move in unison. The curve of the coupler and the groove is the arc of a circle struck from the point 15 as a center, since the wipers swing about that point. Thus it is evident that the wipers may be formed in many ways for performing the same functions.

Having thus explained the nature of the invention and described a way of constructing and using the same, though without attempting to set forth all of the forms in which it may be made or all of the modes of its use, I declare that what I claim is—

- 60 1. In a lasting-machine, in combination, a support, and non-pivoted coacting wipers mounted upon said support and operated automatically by the engagement of a last therewith.
- 65 2. In a lasting-machine in combination, a support, non-pivoted coacting wipers mounted upon said support and automatically op-

erated by the engagement of a last therewith, and means for bringing the last and wipers into engagement.

3. In a lasting-machine, in combination, a stationary support, non-pivoted coacting wipers mounted upon said support and automatically operated by the engagement of a last therewith, and means for forcing a last 75 against said wipers to operate them.

4. In a lasting-machine in combination, a support, non-pivoted coacting wipers mounted upon said support and operated by the engagement of a last therewith, and means for 80 jacking the last against the wipers in a direction transverse to the last.

5. In a lasting-machine, in combination, a support, non-pivoted coacting wipers mounted upon said support and operated by the engagement of a last therewith, and means for separating the rear ends of the wipers to force their operative edges over the last.

6. In a lasting-machine, in combination, a support, non-pivoted coacting wipers mounted upon said support and operated by the engagement of a last therewith, said wipers having inclined rear edges, and means relatively to which the wipers are movable for separating the rear ends of said wipers to force their operative edges over the last.

7. In a lasting-machine, in combination, a support, non-pivoted coacting wipers mounted upon said support and operated by the engagement of a last therewith, and means for causing the wipers to move in unison.

8. In a lasting-machine, in combination, a support having side guides, and non-pivoted coacting wipers mounted upon said support and having their outer edges in rolling contact with said guides.

9. In a lasting-machine, in combination, a support, coacting wipers slidably mounted on said support and disconnected therefrom, and means for engaging a last with the wipers whereby the wipers are automatically operated thereby.

10. In a lasting-machine, in combination, a support, coacting wipers mounted on said support and disconnected therefrom, said wipers being automatically operated by the engagement of a last therewith, and means for coupling the wipers together.

11. In a lasting-machine, in combination, a head, a cap-plate secured to the head, and non-pivoted coacting wipers placed slidably between the head and the cap-plate, said wipers being operated by the engagement of a last therewith.

12. In a lasting-machine, in combination, a head, a cap-plate, coacting wipers confined between said head and said plate, means for coupling the wipers together to move in unison, and means for wedging the rear ends of the wipers, apart, said wipers being operated 130 by the engagement of a last therewith.

13. In a lasting-machine, in combination, a support, coacting wipers mounted on said support and operated by the engagement of

- a last therewith, said wipers having diverging rear inner edges, and means mounted on the support against which said edges are forced when said wipers are operated, to separate the rear ends thereof.
14. In a lasting-machine, in combination, a support, coacting wipers mounted on said support and having diverging rear inner edges, and rotatable means journaled on the support against which said edges are forced when the wipers are operated.
15. In a lasting-machine, in combination, a support, coacting wipers mounted on said support and having diverging rear inner edges formed with rack-teeth, and intermeshing pinions engaged with said rack-teeth.
16. In a lasting-machine, in combination, a support, coacting wipers mounted on said support and having diverging rear inner edges, means for forcing said edges apart, and a spring connecting the rear ends of the wipers.
17. In a lasting-machine, in combination, a support, coacting wipers having opposing operative edges, and a disk coupler for said wipers, which forms a continuation of said operative edges.
18. In a lasting-machine, in combination, a support, coacting wipers having opposing operative edges, and a disk coupler for said wipers, which forms a continuation of said operative edges, and which has its operative surface flush with the operative surface of the wipers.
19. In a lasting-machine, in combination, a support, coacting wipers having rounded outer edges, opposing operative edges, and abutting corners, and means for holding said corners in contact when said wipers are operated, consisting of stationary guides, with which said edges are in rolling contact.
20. In a lasting-machine, in combination, a support, coacting wipers operated automatically by the last and having their front inner corners meeting at a point, said wipers also having opposing operative edges, and means for causing said edges to approach and recede from each other about said point as the center of movement.
21. In a lasting-machine, in combination, a support, coacting wipers having their front inner corners meeting at a point, said wipers having operative inner edges, and outer curved edges, and guides with which said curved edges are in rolling contact.
22. In a lasting-machine, in combination, a support, coacting wipers, a band for clamping the upper against the last, and non-pivoted sliding carriers for said band movable independently of the wipers to permit the band to adjust itself to the last.
23. In a lasting-machine, in combination, a support, coacting wipers, a band for clamping the upper against the last, said band being supported independently of the wipers, and 65 non-pivoted carriers for said band mounted to swing toward each other automatically by the engagement of the last against the band.
24. In a lasting-machine, in combination, a support, coacting wipers, and a freely-sliding 70 non-pivoted band supported independently of the wipers for clamping the upper against the last, said band being mounted to freely adjust itself to differently-shaped lasts.
25. In a lasting-machine, in combination, a 75 support, coacting wipers, a band, and non-pivoted band-carriers slidably mounted upon said support, said carriers being movable independently of each other and of the wipers and being mounted to swing toward and from 80 each other.
26. In a lasting-machine, in combination, a support, a band, band-carriers movable on the support, and separated fulcrums for the said band-carriers whereby when a last is pressed 85 against the band, the carriers are wedged between said fulcrums.
27. In a lasting-machine, in combination, a support, a band, band-carriers movable on the support, and separated spring-pressed fulcrums for the band-carriers between which the carriers may be wedged by the engagement of a last therewith.
28. In a lasting-machine, in combination, a support, a band, non-pivoted band-carriers, 95 and yielding fulcrum-pins for said carriers.
29. In a lasting-machine, in combination, a support, a band, non-pivoted band-carriers, yielding fulcrum-pins for said carriers, and guides for the outer edges of said carriers 100 with which said edges are in rolling contact.
30. In a lasting-machine, in combination, a support, and automatically-operated coacting wipers mounted on the support and a tilting pivot-pin for said wipers.
31. In a lasting-machine, in combination, a support, coacting wipers, a band and band-carriers, and a tilting pin pivoted to the support for supporting the wipers, band, and band-carriers, said pin being oscillatory transversely of the planes of the wipers.
32. In a lasting-machine, in combination, a head, a cap-plate, a tilting rod connected to the cap-plate and pivoted upon said head, coacting wipers, a band, and band-carriers, 115 said wipers, band, and band-carriers being supported by said cap-plate whereby they tilt therewith.
- In testimony whereof I have signed my name to this specification, in the presence of 120 two subscribing witnesses, this 17th day of April, A. D. 1897.
